SCREW PROPELLER

Filed May 19, 1928

Oscar Hermanson.

UNITED STATES PATENT OFFICE

OSCAR HERMANSON, OF NEW YORK, N. Y.

SCREW PROPELLER

Application filed May 19, 1928. Serial No. 279,066.

In the accompanying drawings Fig. 1 shows the propeller in front. Fig. 2 shows one of the ribbons of which the blades are built up. Fig. 3 shows the manner in which the blade is attached to a wooden hub, and Fig. 4 shows the blade attached to a metal hub. Fig. 5 shows a blade made by folding a sheet of metal, shown in Fig. 6, similar numbers referring to similar parts.

10 If a propeller driving some vehicle travels at a rate of a hundred miles an hour, it advances 146.66 . . . feet per second, and if the screw makes 1200 revolutions per minute, or 20 revolutions per second, the pitch, that is the 15 length, measured along the axis, of a complete turn of the thread of the screw, must be at least 7.333 . . . feet or 88 inches, if the screw shall not impede the motion. At this speed the propeller will merely revolve without 20 striking the air, and if it shall have a propelling effect, the speed of the revolving screw must be increased until it overcomes the resistance of the air. Taking, for example, a 25 6 foot propeller with a hub of 4 inches diameter and 5 inches high, the single blade of the propeller, at a pitch of 88 inches, will constitute the $5/88=1/17.6$ th part of the complete screw surface, the thread of the screw around the hub will measure

$$30 \sqrt{88^2 + (4\pi)^2} : 17.6 = 5.05 \text{ inches,}$$

and the thread of the screw at the circumference will measure

$$35 \sqrt{88^2 + (72\pi)^2} : 17.6 = 13.79 \text{ inches,}$$

but we never meet a propeller of this shape, because the manufacturers find no material that is strong enough and stiff enough to withstand the strains in such a shape.

40 Near the periphery where the effect of the screw would be the largest, we see the width of the blade reduced, often to a sharp point, which of course cannot have any effect. Some metal propeller blades, made of drop-forged steel or other alloys, have the shape of a twisted table knife, but looking at wooden propellers, we find on these only in spots true screw faces, while the whole blade represents a clumsy cudgel which, swinging around, is 45 flailing the air and causes a terrible noise in-

stead of a propelling effect. This accounts for the stupendous waste of power on airplanes, and because it is lack of rigidity in the material that so far has defeated the correct shape of propellers, I shall altogether dispense with that rigidity and shall rely only on the tensile strength of the material in my propeller.

Building a light but geometrically correct screw of such material of high tensile strength, this screw may be pliable or may be stiff, but its shape will be maintained while it revolves by the centrifugal force of some weight which I insert at the peripheral edge of the blade.

55 In the foregoing example of a 6 foot propeller, that makes 20 revolutions per second, the material in the peripheral edge of the blade revolves with a velocity of $120\pi = 376.99$ feet per second, but the centrifugal force of 60 a weight W revolving with the velocity v in a circle with radius r is Wv^2/gr , g being the acceleration by gravity or 32.2 feet per second. Therefore the pull of a weight of W pounds 65 revolving with the velocity of 377 feet per second in a circle of 3 feet radius, is $377^2 W / 32.2 \times 3 = 1471.315 W$ pounds. This means every pound at the peripheral rim of the propeller pulls with a centrifugal force of over 70 1471 pounds when the propeller travels with 75 a speed of 100 miles per hour at the lowest number of 20 revolutions per second, when the propeller does no work at all. But in order to maintain that speed of 100 miles per hour, we must increase the number of revolutions and at 1800 revolutions per minute, or 80 30 revolutions per second, because the pull is in proportion to the square of the velocity v , the centrifugal force becomes $9/4 = 2.25$ times 85 greater or 3310.46 pounds for every pound in 90 the peripheral rim.

While this shows the reason why no satisfactory screw can be shaped of wood or other material of similar strength, it at the same time shows that a pliable screw can be built 95 up of band iron or of ribbons of steel of high tensile strength that will be stretched by centrifugal force in revolving, when we reinforce the peripheral rim of the screw with but a few pounds of weight. Reinforcing the 13.79 inch 100

peripheral rim of the afore defined propeller blade with 14 inches of a one half inch rod of lead, which weighs 1.1215 pounds, this will cause a pull of 3712.85 pounds at 1800 revolutions per minute, and if the blade is built up of 14 steel ribbons, each one inch wide, this will give only 265 pounds for each ribbon. But such ribbons of steel will easily hold 50 tons to the square inch, that is to say, they need be no thicker than one three hundredth of an inch.

In Fig. 1 a 6 foot propeller is shown the two blades of which are built up, each of seven two inch wide ribbons, with a hub 1 of 4 inches diameter and 5 inches high. At the periphery the blades are loaded with a $\frac{1}{2}$ inch rod of lead 2, 14 inches long and weighing 1.1215 pounds, exerting a pull of 3712.85 pounds at 1800 revolutions per minute. In Fig. 2 a single ribbon is shown with two holes 3 at its peripheral end, that is slung around the leaden bar and riveted. Fig. 3 shows the manner in which the blade is attached to a wooden hub. Of course, such blades may be attached to the hub in many other ways, and any desired number of blades may be attached to the hub in the same manner. In Fig. 3 the 7 overlapping ribbons that form the blade are shown with their central ends bent at a right angle at the line $a-b$ in Fig. 2 and pressed to the hub 1 by a bar 4 that is tied by wires 5 to the hub 1. In Fig. 4 an angle bar 6 is shown to press the blade to the planed face of the hub. This angle bar 6 is shown to be held by three screw bolts so that the slots 9 allow to revolve it around the fixed center bolt 8 and in this manner to change the pitch of the screw.

When revolving, the ribbons will be strongly pressed against one another by centrifugal force and by the pressure of the air, so that no air will escape between them, which also might be prevented by agglutinating adjacent ribbons by means of any adhesive or elastic material, like rubber.

Instead of building up each blade of many single ribbons, as afore described, I may also build a blade of a single sheet by properly folding it. Fig. 6 shows a single rectangular sheet which is to be cut at the dot and dash lines 10 and is to be bent on one side along the six parallel lines 11, and on the other side along the six dotted lines 12. When folded along these lines, the sheet forms the fan Fig. 5. With 14 holes punched at the bottom of the sheet Fig. 6, the rim will be folded around the rod 13 and riveted, as shown in Fig. 5, while the other end of the folded fan is bent at a right angle and with a bar and seven wires tied to the hub in the manner afore described.

In case the ribbons in Fig. 1 are not stiff enough to hold the blades stretched in place when at rest, I reinforce the blades with light but rigid bars 14, just strong enough to hold

the peripheral rim of the blade at its distance from the hub.

Having described in the foregoing my invention, what I claim as such and desire to secure by Letters Patent, is:

1. In a propeller, a hub, separate blades each made up of a number of ribbons extending radially from said hub and terminating in a weighted peripheral rim whereby the blades are maintained in operative position by centrifugal force.

2. A propeller as claimed in claim 1 wherein in the central end of each ribbon is fastened to an angle bar that is attached to the hub by means of screws passing through slots in the angle bar whereby the pitch of the blades may be adjusted.

OSCAR HERMANSON.
